UNITED STATES PATENT OFFICE.

LEO S. SACK, OF PHILADELPHIA, PENNSYLVANIA, ASSIGNOR TO DURABLE KNITTING MILLS, OF PHILADELPHIA, PENNSYLVANIA, A COPARTNERSHIP CONSISTING OF ABRAHAM L. STOUMEN, ISADORE COHEN, AND HIMSELF.

DESIGN FOR A KNITTED SWEATER.

Application filed March 11, 1927. Serial No. 21,092. Term of patent 3½ years.

To all whom it may concern:

Be it known that I, LEO S. SACK, a citizen of the United States, residing in Philadelphia, county of Philadelphia, State of Pennsylvania, have invented a new, original, and ornamental Design for a Knitted Sweater, of which the following is a specification, reference being had to the accompanying drawing, which forms a part thereof.

Fig. 1 is a front view of a sweater embodying my design. Fig. 2 is a rear view of the upper part of the sweater shown in Fig. 1.

The sweater contains similar distinctive ornamentations applied to different parts thereof, each ornamentation comprising a plurality of longitudinally extending spaced apart rows of block-like figures, adjacent blocks being of colors contrasting with each other and with the body of the sweater.

I claim:

The ornamental design for a knitted sweater as shown and described.

In testimony of which invention, I have hereunto set my hand, at Philadelphia, on this 28th day of February, A. D., 1927.

LEO S. SACK.
